UNITED STATES PATENT OFFICE.

SAM H. LIBBY, OF EAST ORANGE, NEW JERSEY, ASSIGNOR TO GENERAL ELECTRIC COMPANY, A CORPORATION OF NEW YORK.

MEANS FOR CONTROLLING FLUID-COMPRESSORS.

No. 839,609.

Specification of Letters Patent.

Patented Dec. 25, 1906.

Application filed June 6, 1904. Serial No. 211,261.

To all whom it may concern:

Be it known that I, SAM H. LIBBY, a citizen of the United States, residing at East Orange, county of Essex, State of New Jersey, have invented certain new and useful Improvements in Means for Controlling Fluid-Compressors, of which the following is a specification.

My invention relates to the control of pumps or fluid-compressors, and refers particularly to the control of a plurality of pumps or compressors supplying compressed fluid to a common receptacle.

The object of my invention is to provide a control system for automatically maintaining proper pressure and at the same time for dividing the work in proper proportions among the several compressors.

A case to which my invention is applicable is that of an air-brake system on a train in which a plurality of air-compressors at different points on the train supply air to a reservoir-line running the entire length of the train and in which constant pressure must be maintained. It is common practice to provide each air-compressor with an automatic governor which will start the motor driving the compressor whenever the pressure falls below the desired limit and which will stop the motor when the pressure is again raised to the proper amount. In order to distribute the work properly among the several compressors, it is necessary to adjust the several governors with care, so that they will respond simultaneously to variations in pressure.

The object of my invention is to provide a novel form of governor and a novel arrangement of the control system which shall render unnecessary a careful adjustment of the governors. The governor is connected both to the reservoir-line and to the reservoir charged from the compressor controlled by the governor, and a check-valve is placed between the reservoir and the reservoir-line. By means of the check-valve air is prevented from flowing from the line to the reservoir, and the governor is arranged to respond not only to a fall of pressure in both reservoir and reservoir-line, but also to a difference in the pressure between the two. Thus if one governor responds before the rest and starts its compressor at work, raising the pressure in

the line, this pressure can have no effect upon the other reservoirs, and the difference in pressure created between the train-line and the other reservoirs produces an immediate response of the other governors, which set their respective compressors at work to charge their reservoirs. In this way the work is properly distributed among the several compressors.

My invention will best be understood by reference to the accompanying drawings, in which—

Figure 1 shows diagrammatically an arrangement embodying my invention as applied to the control of a plurality of compressors jointly supplying a reservoir-line. Fig. 2 shows a front elevation of the differential governor. Fig. 3 shows a side elevation of the same partly in cross-section, and Fig. 4 shows a plan view of the contacts carried at the tip of the governor-levers.

In Fig. 1 I have shown the equipment for two cars of the train. L represents the reservoir-line extending the length of the train and supplied from the reservoirs R R', which are charged from the compressors C C', driven by the motors M M'. S represents a solenoid or magnet-coil controlling the switch s in the circuit of motor M. The core of solenoid S also carries the bridging member s'. I represents a resistance, and b a blow-out coil for the switch s. D represents the differential governor, which comprises two diaphragms d and d', which are connected to the reservoir R and the reservoir-line L by the pipes r and l, respectively. V represents a check-valve inserted between the reservoir R and reservoir-line L, permitting a free flow of air from reservoir to line and preventing the flow in the opposite direction. The check-valve V' is shown in cross-section. T represents the trolley, collector-shoe, or other source of current for the circuit of motor M.

Neglecting for a moment the construction and arrangement of the differential governor D, the general operation of the system will be briefly described.

With normal pressure in reservoir-line L and in reservoirs R and R' solenoids S and S' are both deenergized, and the circuits of both motors M and M' are open. Now assume that the air is exhausted from the reservoir

line, so as to lower the pressure below the minimum limit. The pressure in both reservoirs R and R' will also be lowered. Now assume that the differential governor D responds to the lowering of pressure before differential governor D'. Solenoid S will then be energized by a circuit from trolley T to upper terminal of solenoid S through the entire winding and from the lower terminal 10 through conductor 3 and the contacts of differential governor D to earth E. Solenoid S will consequently raise its core, closing switch s, thereby starting the motor and at the same time raising the bridging member 15 s' and closing a maintaining-circuit for itself from trolley T, upper terminal of solenoid S, middle terminal, resistance I, bridging member s' to earth. Motor M will consequently start, driving controller C and raising the 20 pressure in reservoir R and in reservoir-line L. Check-valve V' will prevent the flow of air from reservoir-line to reservoir R', so that the pressure in reservoir R' will not be raised. A difference of pressure will then exist on 25 the two diaphragms d^2 and d^3 of differential governor D'. As has already been stated, and as will hereinafter be explained, the differential governor is responsive to a difference in pressure, as well as to a simultaneous 30 variation of pressure, on the diaphragms. Consequently differential governor D' will close the circuit of solenoid S', which will start the motor M' and close its own maintaining-circuit in a manner heretofore described. This will continue until the maximum limit of pressure is reached in the two reservoirs and in the reservoir-line. When 35 this limit is reached, the differential governors act to connect the lower terminals of solenoids S and S' to the trolley T and T'. Current is then passing in opposite directions in the two halves of the solenoids. The cores are consequently deenergized, and the motor-circuits are opened, stopping the operation of the compressors.

Referring now to Figs. 2 and 3, d and d' represent the two diaphragms, which are connected by the pipes r and l to reservoir and to reservoir-line, respectively. The diaphragms are shown in Fig. 3 in low-pressure position. When the pressure rises in pipes r and l , the two diaphragms are pushed forward to engage pistons e and e' , respectively, which carry spindles bearing against the pivoted arm F and the pivoted link g, respectively, which are held pressed against the spindles by the springs J and J'. Arm F is pivoted at f, and the link g is pivoted at g'. G is a second arm, which is pivoted at f^2 to arm F and at g^2 to the link g. The arm F carries at its upper end two contacts i and i' , and arm G carries the single contact k , as shown in Fig. 4. The contact i is connected by conductor 1 to earth, as indicated in Fig.

1. Contact i' is connected by conductor 2 to 65 the upper terminal of solenoid S, as shown in Fig. 1, and contact k is connected by the conductor 3 to the lower terminal of solenoid S.

The operation is as follows: With the diaphragms in the low-pressure position shown, 70 arm F and link g are both pushed inwardly in the position shown by the spring J and J', respectively. Since the pivots f^2 and g^2 are both pressed inward an equal amount, the lever-arm G is not deflected from its vertical 75 position. The arm F, however, is deflected, as shown in Fig. 3, so as to bring contact i into engagement with contact k . This connects the lower terminal of solenoid S to ground, so as to energize the solenoid and 80 close the motor-circuit, as has been theretofore explained. If the pressures in pipes r and l rise at an equal rate, pistons e and e' will be pushed outward at the same rate and pivots f^2 and g^2 will travel at the same rate 85 also, so that arm G will still maintain its vertical position. The outward movement of piston e , however, produces a movement of arm F, so as to withdraw contact i from contact k . The lower terminal of solenoid S 90 is consequently disconnected from ground; but the solenoid remains energized, since it has closed its own maintaining-circuit, as has been heretofore explained. This continues until arm F has been moved such a distance as to bring contact i' into engagement with contact k . A circuit is then closed from the trolley T to the lower terminal of the solenoid, whereupon the solenoid is deenergized and opens the motor-circuit, as has 95 been heretofore explained. Thus if the pressure rises simultaneously and at an equal rate in reservoir and reservoir-line, the governor acts as a simple governor, opening and closing the motor-circuits when the upper and lower pressure limits are reached, one of the arms remaining practically stationary and the other responding to variations in pressure in both reservoir and reservoir-line. If, however, the pressure at any 100 time is not equal in pipes r and l , a movement of the pivoted arm G is produced. If, for instance, while contact k is midway between contacts i and i' and the motor-circuit is open the pressure in the reservoir-line 105 falls a sufficient amount to cause one of the other governors to respond, so as to start its compressor, the pressure in pipe L will be increased, while the pressure in reservoir R will not be changed, owing to the presence of check-valve V of Fig. 1. Pivoted link g will consequently be pushed outward by diaphragm d' , while pivoted arm F will remain stationary. Pivot f^2 consequently remains 110 stationary, while pivot g^2 moves outward. A movement of arm G is thereby produced, so as to bring contact k into engagement 115 with contact i . The solenoid is then energized and opens the motor-circuit. If, on the other hand, the pressure in reservoir R increases 120 while the pressure in reservoir-line L remains stationary, the pressure in pipe L will be increased, while the pressure in reservoir R will not be changed, owing to the presence of check-valve V of Fig. 1. Pivoted link g will consequently be pushed outward by diaphragm d , while pivoted arm F will remain stationary. Pivot f^2 consequently remains 125 stationary, while pivot g^2 moves outward. A movement of arm G is thereby produced, so as to bring contact k into engagement with contact i' . The solenoid is then energized and opens the motor-circuit.

gized, so as to close the meter-circuit. Arm G is slotted at pivot f^2 , as shown in dotted lines, in order to permit of relative movement between pivots f^2 and g^2 . Thus it will be seen that one of the two arms responds to the simultaneous variation of pressure upon the two diaphragms, and the other arm responds to a relative variation of pressure upon the two diaphragms, and that by means of this differential action an equal division of load among the several compressors may be obtained. By means of the set-screws j and j' , (shown in Fig. 3) the pressure of springs J and J' may be adjusted, thereby adjusting the action of the governor.

Although I have shown my invention as applied to an air-brake system on trains, it is evident that it is not limited to this particular application, but may be used to advantage wherever a plurality of pumps or fluid-compressors are employed to supply a given fluid-receptacle. Furthermore, the construction and arrangement of parts may be greatly modified without departing from the spirit of my invention, and I aim in the appended claims to cover all such modifications. For instance, the diaphragms may be simple diaphragms, as shown, or any other suitable device responsive to variations in fluid-pressure may be employed, and by the term "diaphragm" in the appended claims I intend to cover all devices, whether simple diaphragms or not, which respond to variations in fluid-pressure.

What I claim as new, and desire to secure by Letters Patent of the United States, is—

1. In combination, a plurality of fluid-compressors, a common receptacle supplied thereby, check-valves between the several compressors and said receptacle, and governors controlling the several compressors, each of said governors being responsive both to simultaneous and to relative variations of pressure in the compressor and receptacle.

2. In combination, a plurality of reservoirs, a common receptacle supplied thereby, check-valves between the several compressors and said receptacle, compressors for charging the several reservoirs, and governors controlling the several compressors, each of said governors being responsive both to simultaneous and to relative variations of pressure in the reservoir and receptacle.

3. In an air-brake system, a reservoir-line, a plurality of reservoirs for supplying said line, check-valves between said line and the several reservoirs, compressors for charging the several reservoirs, and governors controlling the several compressors, each of said governors being responsive both to simultaneous and to relative variations of the pressure in the reservoir and reservoir-line.

4. In an automatic pressure-governor, two diaphragms subjected to pressures from

different sources, levers actuated by the movement of said diaphragms and arranged to respond both to a simultaneous and to a relative movement of said diaphragms, and controlling mechanism controlled by the movement of said levers.

5. In an automatic pressure-governor, two diaphragms subjected to pressures from different sources, levers actuated by the movement of said diaphragms, one of said levers responding to a simultaneous movement and another to a relative movement of said diaphragms, and controlling mechanism controlled by the relative movement of said levers.

6. In an automatic governor, two diaphragms subjected to pressures from different sources, levers actuated by the movement of said diaphragms and arranged to respond both to a simultaneous and to a relative movement of said diaphragms, a contact carried by one lever, and two contacts carried by a second lever and arranged to be brought respectively into engagement with the first contact upon a relative movement of said levers in one direction or the other, and an electroresponsive controlling device controlled by said contacts.

7. In an automatic pressure-governor, two diaphragms subjected to pressures from different sources, levers actuated by the movement of said diaphragms, one of said levers responding to a simultaneous movement and another to a relative movement of said diaphragms, a contact carried by one of said levers, two contacts carried by the second lever and arranged to be brought respectively into engagement with the first contact upon a relative movement of said levers in one direction or the other, and an electroresponsive controlling device controlled by said contacts.

8. In an automatic pressure-governor, two diaphragms subjected to pressures from different sources, a pivoted lever actuated by one diaphragm, a pivoted link actuated by the other diaphragm, a second lever carried jointly by said link and the first lever, and controlling mechanism controlled by said levers.

9. In an automatic pressure-governor, two diaphragms subjected to pressure from different sources, a pivoted lever actuated by one diaphragm, a pivoted link actuated by the other diaphragm, a second lever carried jointly by said link and the first lever, contacts carried by said levers, and an electroresponsive controlling device controlled by said contacts.

10. In combination, a plurality of reservoirs, a common receptacle supplied thereby, check-valves between the several reservoirs and said receptacle, compressors for charging the several reservoirs and governors con-

trolling the several compressors, each of said governors comprising two diaphragms subjected respectively to the pressures of the reservoir and the receptacle, and levers controlled by the movement of said diaphragms.

11. In combination, a plurality of reservoirs, a common receptacle supplied thereby, check-valves between the several reservoirs and said receptacle, compressors for charging the several reservoirs and governors controlling the several compressors, each of said governors comprising two diaphragms subjected respectively to the pressures of the reservoir and the receptacle, and levers actuated by the movement of said diaphragms and arranged to respond both to simultaneous and to relative movement of said diaphragms.

12. In combination, a plurality of reservoirs; a common receptacle supplied thereby, check-valves between the several reservoirs and said receptacle, compressors for charging the several reservoirs and governors controlling the several compressors, each of said governors comprising two diaphragms subjected respectively to the pressures of the reservoir and the receptacle, and levers actuated by the movement of said diaphragms, one of said levers being responsive to a simultaneous movement and another to a relative movement of said diaphragms.

13. In an apparatus of the character described, the combination with an air-pump, a main reservoir, and a main-reservoir pipe-line connected to said reservoir with means for preventing backflow to the reservoir, of a movable abutment operated by main-reservoir pressure for controlling said pump, and means operated through the pressure of the main-reservoir pipe-line for also controlling said pump.

14. In an apparatus of the character described, the combination with an air-pump, a main reservoir, and a main-reservoir pipe-line connected to said reservoir with means for preventing backflow to the reservoir, of a movable abutment operated by main-reservoir pressure for controlling said pump, and means operated through the pressure of the main-reservoir pipe-line for controlling the action of said movable abutment.

15. In an apparatus of the character described, the combination with an air-pump, a main reservoir, and a main-reservoir pipe-line connected to said reservoir with means for preventing backflow to the reservoir, of means operated by the opposing pressures of the main reservoir and the main-reservoir pipe-line for controlling said pump.

16. In a braking system, a reservoir-line, a reservoir, a pump, and means positioned between said reservoir-line and said pump adapted upon an increase in pressure taking

place in said reservoir-line to cause the operation of said pump.

17. In a braking system, a reservoir-line, a reservoir, a pump, and means positioned between said reservoir-line and said pump adapted upon an increase in pressure taking place in said reservoir-line to cause said pump to force air into said reservoir.

18. In a braking system, a reservoir-line, a reservoir, a pump, and means positioned between said reservoir-line and said pump adapted upon an increase in pressure taking place in said reservoir-line to complete an electric circuit controlling the operation of said pump.

19. In a braking system, a reservoir-line, a reservoir, a pump, and means adapted upon an increase in pressure taking place in said reservoir-line to cause said pump to force air into said reservoir.

20. In a braking system, a reservoir-line, a plurality of reservoirs, a plurality of pumps, and means positioned between each of said reservoirs and said reservoir-line adapted upon an increase in pressure taking place in said reservoir-line to cause the corresponding pump to force air into the corresponding reservoir.

21. In a braking system, a reservoir-line, a reservoir, a pump, means adapted upon the fall of pressure in said reservoir-line to a certain predetermined point to cause said pump to force air into said reservoir, and means adapted upon the pressure in said reservoir-line exceeding that in said reservoir to cause a similar action of said pump.

22. In a controlling apparatus, two receptacles adapted to contain a fluid under pressure, a connection between the same, and means positioned in said connection adapted upon the pressure in one of said receptacles increasing to complete an electric circuit.

23. In a controlling apparatus, two receptacles adapted to contain a fluid under pressure, a connection between the same, and means positioned in said connection adapted upon the pressure in one of said receptacles becoming greater than that in the other to complete an electric circuit.

24. In a controlling apparatus, two receptacles adapted to contain a fluid under pressure, a connection between the same, and means positioned in said connection adapted upon the pressure in one of said receptacles becoming greater than that in the other to cause the operation of means adapted to increase the pressure in said other receptacle.

In witness whereof I have hereunto set my hand this 1st day of June, 1904.

SAM H. LIBBY.
